(57) **CLAIM**

An ornamental design for an insertable control module, as shown and described.

DESCRIPTION

FIG. 1 is a top view of a first embodiment of an insertable control module showing a top face thereof;

FIG. 2 is a bottom view of the insertable control module shown in FIG. 1;

FIG. 3 is a top view of a second embodiment of the insertable control module showing a top face thereof;

FIG. 4 is a bottom view of the insertable control module shown in FIG. 3;

FIG. 5 is a front view of the insertable control module;

FIG. 6 is a rear view of the insertable control module;

FIG. 7 is a left view of the insertable control module; and,

FIG. 8 is a right view of the insertable control module.

The details shown in broken lines in FIG. 2 are shown for illustrative purposes only and form no part of the claimed design.
